UNITED STATES PATENT OFFICE.

DEVILLO WASHINGTON NORTHRUP, OF UTICA, NEW YORK.

MANUFACTURING FELTED MITTENS FROM WOVEN OR KNITTED FABRIC.

SPECIFICATION forming part of Letters Patent No. 292,250, dated January 22, 1884.

Application filed March 3, 1883. (No model.)

To all whom it may concern:

Be it known that I, DEVILLO W. NORTHRUP, of Utica, in the county of Oneida and State of New York, have invented certain new and useful Improvements in Manufacturing Felted Mittens from Woven or Knitted Fabric; and I do hereby declare the following to be a full, clear, and exact description of the invention, such as will enable others skilled in the art to which it appertains to make and use the same.

My invention relates to an improvement in mittens, and to an improved process of manufacturing them, the object being to produce articles of this character which shall combine the warmth, durability, and impermeability of felt with the elasticity and pliability of knitted or woven fabric, and which shall be neat in appearance and comfortable to wear.

With these objects in view my invention consists in mittens composed of felted, knitted, or woven fabric.

My invention further consists in a process of making mittens, consisting, essentially, in constructing an exaggerated article from knitted or woven fabric, then fulling the article so constructed, and finally blocking it, if need be.

My invention further consists in certain details of construction and operation, as will be more fully hereinafter set forth and described.

In the accompanying drawings, Figure 1 is a view in perspective of a section of tubular knitted fabric, the same having one end rounded for the end of the mitten, and having a slit cut in it for the attachment of the thumb. Fig. 2 is a view in elevation, showing the mitten in the second stage of its formation, in which the rounded end is knitted or sewed together and the thumb attached. Figs. 3 and 4 respectively represent the mitten after the processes of fulling and blocking.

A represents a section of tubular knitted fabric, one end thereof being rounded, and then sewed, knitted, or otherwise closed up. The said section is provided with a slit, B, to the edges of which the thumb C is attached.

The thumb may be formed from a section of tubular fabric of suitable size, or from flat

knitted or woven fabric, or yet it may be knitted onto the section by hand or by suitable mechanism. So far as the section A is concerned, it may be formed from flat knitted or woven fabric, as well as from tubular fabric, although the latter is preferred, as it requires less seaming. After the exaggerated mitten has been completed, it is fulled in any approved manner, and preferably by the use of soap and water. During this operation the toothed edges of the fabric are interlocked and so intimately associated with each other that the mesh of the fabric disappears by gradual incorporation. The seams are completely obliterated, and the mitten contracts in every direction and increases in thickness and compactness of texture until, when the process of fulling is ended, the mitten has the appearance of being formed from a single piece of felt. The size of the completed mitten will depend, within certain limits, upon the duration of the operation of fulling, which may be timed accordingly, and upon the size of the mitten before fulling. After the operation of fulling, the mittens are blocked to give them shape, if such a course is necessary.

In mittens fabricated in accordance with my invention the warmth, durability, and impermeability of felt are combined with the elasticity and pliability of knitted and woven fabric. The mittens are seamless, and hence comfortable and neat in appearance, and they will not fray nor ravel.

It is apparent that the process herein described is applicable to the manufacture of gloves, as well as to that of mittens; hence I would have it understood that I consider gloves to be embraced by my invention.

Having fully described my invention, what I claim as new, and desire to secure by Letters Patent, is—

1. As a new article of manufacture, a mitten composed of knitted or woven fabric felted or fulled, substantially as set forth.
2. A process of making mittens, consisting, essentially, in constructing an exaggerated article from knitted or woven fabric, then fulling the article so constructed, and finally blocking it, if need be, substantially as set forth.
3. A process of making mittens, consisting,

essentially, in constructing an exaggerated article from woven or knitted fabric by appropriately cutting and seaming the same, then fulling the article so constructed, and finally 5 blocking it, if need be, substantially as set forth.

In testimony whereof I have signed this

specification in the presence of two subscribing witnesses.

DEVILLE WASHINGTON NORTHRUP.
